Des. 738

Calvin Fulton of Rochester, N.Y. Assign to Sam'l McElveen of Rochester, aforesaid & Bedell & Barry of Albion. Letters Patent No. 738 - dated Oct. 30th 1855.

The schedule referred to in these Letters Patent, is making part of the same.

To all whom it may concern,

Be it known that I, Calvin Fulton, of the City of Rochester, County of Monroe, & State of New York, have invented or produced a new Ornamental Design for a Stove Plate, known as the Pearl of Rochester, & I do hereby declare that the following is a full, & exact description thereof, reference being had to the accompanying drawings, & to the Letters of reference marked thereon, in which

Fig. 1. is a front elevation of my stove-plate.

Fig 2. is a section through A. B. Fig 1.

C. Fig 2. is a section of the moulding C. Fig 1.

D. Fig 2. is a section of the scroll D. Fig 1. E. F. & G. Fig 2. show a section of the flower, E. F. & G. Fig 1. H. Fig 2. is a section of the scroll H. Fig 1. I. Fig 2. is a section of the moulding I. Fig 1.

What I claim as my invention, and desire to secure by Letters Patent, is the ornamental design of a stove-plate, substantially as herein described and represented.
